UNITED STATES PATENT OFFICE

WILLIAM EDWARD RICHARD, OF EVANSVILLE, INDIANA, ASSIGNOR TO SUNBEAM ELECTRIC MANUFACTURING COMPANY, OF EVANSVILLE, INDIANA, A CORPORATION OF INDIANA

COOLING SYSTEM FOR INTERNAL COMBUSTION ENGINES

Application filed September 1, 1928. Serial No. 303,457.

This invention relates to cooling systems for internal-combustion engines and has particular relation to a novel means and method for automatically regulating the effect of cooling fluid that is circulated in fluid-cooled engines of the character specified.

The detrimental effects of operating internal-combustion engines at relatively low temperatures are well known. Some of the most important of these are decreased power, increased fuel consumption and excessive dilution of the lubricating oil in the crank case of the engine.

The usual practice in relation to fluid-cooled engines is to admit the cooling fluid near the bottom of the jacket surrounding the cylinder or cylinders of the engine, and to conduct this fluid away from the jacket from a point near the top of the same. Since the amount of cooling fluid that is circulated through the engine must be great enough to cool the engine under the most adverse conditions, the engine normally operates at relatively low temperature. Regulating valves requiring the attention of an operator and automatically operated thermostatic valves are sometimes used, but the provision of such means involves considerable expense and complication of the mechanism.

The present invention contemplates the provision of means whereby the cooling fluid is by-passed around the cylinder jacket without circulating therethrough until the cooling fluid surrounding the cylinder becomes heated and begins to circulate with a thermosiphon action. When this action is established a smaller quantity of the cooling fluid is by-passed and a greater quantity is circulated through the cylinder jacket. The proportion of the fluid that is circulated through the cylinder jacket is automatically regulated, during all of the time that the engine is operating, to maintain the engine at a substantially constant operating temperature of any desired value.

The principal object of the invention is to accomplish the above indicated results by the utilization of a most simple and economical construction of the engine and its accessories.

The invention will be better understood by

reference to the following detailed description, taken in connection with the accompanying drawings, in which:

Fig. 1 is a fragmentary front elevational view showing a portion of an internal-combustion engine cylinder having a fitting embodying the present invention mounted thereon;

Fig. 2 is a vertical sectional view taken along the line 2—2 of Fig. 1;

Fig. 3 is a fragmentary sectional view of a modified form of the invention, taken along a line corresponding to the line on which Fig. 2 is taken; and

Fig. 4 is a fragmentary sectional view, also taken along a line corresponding to that on which Fig. 2 is taken, and illustrating another modification of the invention.

Referring first to Figs. 1 and 2 of the drawings, a portion of a cylinder 5 is shown with a cylinder head 6 mounted thereon, a cylinder head gasket 7 being interposed between these parts in the customary manner. For the sake of simplicity the usual bolts or similar means for securing the cylinder head to the cylinder, as well as the valve and ignition mechanism of the engine and other parts unrelated to the present invention, are omitted from the drawings.

The cylinder 5 comprises an outer jacket portion 8, which is normally cast integrally with the cylinder, and which defines a suitable space or chamber 9 for the circulation of cooling fluid around the cylinder. The cylinder head 6 similarly comprises a jacket portion 10 which defines a space or chamber 11 for the further circulation of cooling fluid. Suitable openings 12 in the top of the chamber 9 register with corresponding openings 13 and 14, which are respectively disposed in the bottom of chamber 11 and in the gasket 7.

The jacket portion 10 of the cylinder head 6 is so shaped as to form an integral flange portion 15 to which a fitting member 16 may be suitably secured, as by bolts or cap screws.

17. A fluid-proof gasket 18 is preferably disposed between the flange 15 and the fitting member 16. The fitting member 16 has a cavity 19 therein registering with an opening 20 through the flange 15, which opening

communicates directly with the cooling-fluid chamber 11 in the cylinder head 6. A cooling-fluid supply conduit 21 is suitably connected to the bottom of the fitting member 16 5 and communicates directly with the cavity 19 in said member. A conduit 22 is similarly connected with the top portion of the fitting member 16 and likewise communicates directly with the cavity 19.

10 Within the cavity 19 in the fitting member 16, and extending inwardly from the front wall of said cavity, is a deflector or baffle 23, which is shown as being formed integrally with the member 16. It is contemplated, 15 however, that this deflector or baffle may be separately formed, and, if desired, may be made movable with respect to the member 16 to permit an adjustment of its position to 20 vary the effectiveness of the same according to the concept of the invention.

During the operation of the engine, cooling fluid is supplied through the conduit 21 by means of a pump (not shown) or any other suitable means. Until the temperature of the 25 engine begins to rise this fluid will simply pass around the deflector or baffle 23 and will be conducted away by the conduit 22 without circulating through the chambers 9 and 11. The temperature of the stagnant cooling fluid 30 within these chambers will, therefore, rise in a very short time. The increase in temperature of this fluid establishes a thermo-siphon action within the chambers 9 and 11 which results in a flow of the heated fluid toward the 35 conduit 22 through which it is removed. Relatively cool fluid then passes from the conduit 21 into the chambers 9 and 11 to effect the required cooling of the engine.

The proportion of the total flow of cooling 40 fluid that is circulated through the chambers 9 and 11 is thus automatically regulated in accordance with the temperature of the engine. A rise in this temperature effects an increase in the circulation of fluid through 45 the cooling chambers, and a lowering of this temperature effects a decrease in the circulation. It will be apparent, therefore, that the actual operating temperature of the engine will be automatically maintained with- 50 in very narrow limits, regardless of variations in load in the engine and regardless of the rate of supply of cooling fluid through the conduit 21. In actual operation it has also been found that variations in the temperature 55 of the cooling fluid as it is supplied to the engine have substantially no effect upon the temperature of the engine itself.

Since the deflector or baffle 23 directs the flow of cooling fluid from the conduit 21 to- 60 ward the cooling chambers 9 and 11 during the time that the engine is operating and the above described thermo-siphon action is tak- 65 ing place, the size of this deflector or baffle determines the proportion of the total flow of cooling liquid that is circulated around the

engine cylinder. The engine may be caused to operate at substantially any desired tem- 70 perature by varying the size of this deflector or baffle. This variation in size may be ef- fected by interchanging fitting members 16 having different sized deflectors or baffles 75 therein, or by making the deflector or baffle movable with respect to the fitting member 16, whereby its operating position may be changed by suitable adjusting means.

Fig. 3 shows a modification of the invention in which a fitting member 24 is secured to the flange member 15 of the cylinder head 6 in the same manner that the fitting member 16 is secured as shown in Figs. 1 and 2. In the form of invention shown in Fig. 3, the fluid supply conduit 21 enters the fitting member 24 horizontally, with a result that the cooling fluid is more directly conducted into the cooling chambers 9 and 11. The fluid outlet con- 80duit 22 is disposed in the same relative position as shown in Figs. 1 and 2. In this form of the invention it is not ordinarily neces- 85sary to utilize a deflector or baffle, such as that shown at 23 in Fig. 2, although it will be ap- 90parent that such a member could be provided if desired.

A still further modification of the invention is shown in Fig. 4. This modification consists in providing an upwardly protrud- 95ing portion 25 on the top of the cylinder head jacket 10. This upwardly protruding portion forms a cavity 26 above the center of the cooling chamber 11, into which cavity the fluid supply conduit 21 and the fluid outlet 100conduit 22 extend. The operation of this form of the invention is substantially the same as that of the forms shown in Figs. 1 and 2.

From the foregoing description it will be 105 seen that the present invention comprehends means that are extremely simple and eco- nomical in construction, whereby the oper- ating temperature of an internal-combustion engine may be automatically maintained sub- 110stantially at a predetermined value, regard- less of all other variable factors. The ad- vantages of utilizing such means will be ap- 115parent for numerous types of engines to any of which the invention may be applied.

While only certain specific modifications of the invention have been shown and de- 120scribed herein, it will be readily understood that numerous changes and modifications may be made in the details of construction and arrangement of parts without departing from the spirit and scope of the invention as set forth in the appended claims.

What is claimed as new and is desired to 125secure by Letters Patent is:

1. A fluid-cooled internal-combustion en- gine comprising a cylinder having a cooling- fluid jacket, means for supplying cooling fluid to said jacket substantially at the top thereof, means connected with said jacket 130

substantially at the top thereof and substantially in alignment with said fluid-supplying means for conducting said fluid away from said jacket, and a deflector or baffle disposed between said fluid-supplying means and said means for conducting the fluid away from the jacket.

2. An internal-combustion engine comprising parts to be cooled, chambers surrounding said parts, a fitting having a cavity therein, means for securing said fitting to the engine in such manner that said cavity is in communication with said chambers, and fluid-supply means and fluid-outlet means communicating with said cavity in substantial alignment with each other.

3. An internal-combustion engine comprising parts to be cooled, chambers surrounding said parts, a fitting having a cavity therein, means for securing said fitting to the engine in such manner that said cavity is in communication with said chambers, fluid-supply means and fluid-outlet means communicating with said cavity, and a deflector or baffle between said fluid-supply means and said fluid-outlet means.

4. An internal-combustion engine comprising parts to be cooled, chambers surrounding said parts, a fitting having a cavity therein, means for securing said fitting to the engine in such manner that said cavity is in communication with said chambers, fluid-supply means and fluid-outlet means communicating with said cavity in substantial alignment with each other, and a deflector or baffle between said fluid-supply means and said fluid-outlet means.

5. An internal-combustion engine comprising parts to be cooled, chambers surrounding said parts, a fitting having a cavity therein, means for securing said fitting to the engine in such manner that said cavity is in communication with said chambers, fluid-supply means and fluid-outlet means communicating with said cavity, and a deflector or baffle formed integrally with said fitting and disposed within said cavity between said fluid-supply means and said fluid-outlet means.

6. An internal-combustion engine comprising parts to be cooled, chambers surrounding said parts, a fitting having a cavity therein, means for securing said fitting to the engine in such manner that said cavity is in communication with said chambers, fluid-supply means and fluid-outlet means communicating with said cavity in substantial alignment with each other, and a deflector or baffle formed integrally with said fitting and disposed within said cavity between said fluid-supply means and said fluid-outlet means.

7. An internal-combustion engine comprising parts to be cooled, chambers surrounding said parts, a fitting having a cavity therein, means for securing said fitting to the engine

in such manner that said cavity is in communication with said chambers, fluid-supply means and fluid-outlet means communicating with said cavity in substantial alignment with each other, and a deflector or baffle formed integrally with said fitting and disposed within said cavity between said fluid-supply means and said fluid-outlet means and substantially in a plane perpendicular to the direction of flow of fluid through said supply and outlet means.

In witness whereof, I have hereunto subscribed my name.

WILLIAM EDWARD RICHARD.
